UNITED STATES PATENT OFFICE.

SYDNEY B. AUSTIN, OF MOUNTAIN LAKES, NEW JERSEY, ASSIGNOR TO THE KNYSCHERER CORPORATION OF AMERICA, OF NEW YORK, N. Y., A CORPORATION OF NEW YORK.

SPLINT STRETCHER.

Application filed May 2, 1923. Serial No. 636,049.

To all whom it may concern:

Be it known that I, SYDNEY B. AUSTIN, a citizen of the United States, residing at Mountain Lakes, in the county of Morris and State of New Jersey, have invented certain new and useful Improvements in Splint Stretchers, of which the following is a specification.

My invention relates to a splint stretcher, 10 and the novelty consists in the adaptation and arrangement of the parts, as will be more fully hereinafter pointed out.

Splint stretchers have been used for many years, and they are used more particularly in connection with warships where accidents frequently occur requiring their use.

For such use on warships it is essential that such splint stretchers should take up as little space as possible when they are not 20 in use and are packed away.

It is essential in the handling of fractures temporarily set before transporting so as to reduce pain and the possibility of badly set bones, to so handle the patient that it 25 will not be necessary to again lift or turn the patient after he has once been placed on a splint stretcher and the bones temporarily set.

My device furnishes such a splint stretcher, 30 which can be readily separated substantially at the middle so that the patient need not be lifted or rolled after he has been carried on my stretcher, but can be laid upon the operating table or bed in my 35 stretcher, which can then be taken apart and the head and foot portions easily slipped out from under the patient without in any way disturbing him.

My device also furnishes a splint stretcher, 40 which can be readily separated so that it can be nested for packing, and it is also constructed so that it furnishes a sanitary opening better adapted to meet all requirements.

Referring to the drawings Figure 1 is a 45 top plan view of my device; Figure 2 is a detail of the telescoping separable connection of the outer frame members; Figure 3

is a detail of the telescoping separable connection of the middle frame members; Figure 4 is a perspective of the entire frame 50 of my device; Figure 5 is a perspective of the foot-rest of my device; and Figure 6 is a top plan view of the frame as shown in Figure 4, which has been separated and nested.

In the drawings 10 is an outer frame member, which I prefer to construct of tubing, and on which are mounted larger tubing members 11 prior to the shaping of the frame 10 so that they can be placed in 55 the positions as indicated to serve as handles. Longitudinal frame members 12, preferably of half round metal, are adapted to be secured at 13 to the frame 10 by being bent thereover and brazed thereto. Cross 60 frame members 14, similar to longitudinal members 12, are adapted to be secured to the frame 10 at 15 in the same manner as the longitudinal members 12 are secured at 13. A pair of cross frame members 16 are 65 secured at 17 to the frame 10 in a manner similar to the securing of the longitudinal members at 13, and these cross members 16 come up in the middle to a point 18 so as to support an additional longitudinal frame member 19 which is secured at 20 to the frame 10 and also to the points 18 in the cross frame members 16.

The outer frame 10 is made separable at the points 21, and the longitudinal frame 80 members 12 are also made separable at the points 27 in alignment with the points 21, thereby making a head frame 25 and a complete foot frame 26 of the two separable portions of my splint stretcher.

The openings 21 comprise a telescoping member consisting of a tongue 22 rigidly secured inside of the frame 10 of the head member 25 so as to project into the interior of the frame 10 of the adjoining foot portion 26. The tongue member 22 has a circular boring 23 which in the closed position is adapted to register with a circular boring 24 in the adjoining foot portion 26 so that

they can be locked together by a cotter pin 28 held on the end of a chain member 29 which is rigidly secured to the cross frame members 14 at 30. The longitudinal frame members 12 of the head portion 25 of the frame terminate at 27 in cylindrical tubes 31 having circular borings 32 which register with semi-circular cut-outs 33 in the adjacent longitudinal frame members 12 which 10 extend into the tubular members 31 so that cotter pins 28 can pass therethrough in the closed position so as to lock them rigidly together.

A wire mesh 34 is adapted to be secured 15 to the outer frame member 10 and the longitudinal frame member 19 of the foot portion 26 on the inside thereof so as to be supported on said frame members. A similar wire mesh 35 is secured to the outer 20 frame member 10 of the head portion 25 on the inside of the frame so as to be supported on said frame member. Chains 36 are adapted to be secured to said mesh 35 and the cross frame members 14 as indicated, 25 and flexible strapping members 37 are adapted to be passed under said chains 36, said members 37 having the usual buckle fastening means 38.

In the foot portion 26 of my device there 30 are chains 39 secured to the mesh 34 and the cross frame members 16. Foot support members 40 having fastening means 41 are adapted to be secured by said fastening means 41 being snapped into the particular 35 link on the chains 39 at the position desired so as to properly support the feet of the person laid on my stretcher as shown in Fig. 1.

In using my splint stretcher the person 40 to be handled is placed on the stretcher as shown in Figure 1, and the foot supports 40 are adjusted to the position on the chains 39 to the position necessary to bring them in support of the feet of the person lying on the stretcher and are then secured to the 45 chains 39 in said positions. The straps 37 are brought around the body of the person lying on the stretcher and strapped into position so as to hold the person on the stretcher in a comfortable fixed position so 50 that he will not roll or be moved in carrying him. When the person to be treated has been carried on my stretcher to the operating room or other place where he is to be treated the straps 37 will be unfastened and 55 the foot supports 40 will be slid away from the feet and the cotter pins 28 being withdrawn from the holes 24 and 32, the head portion 25 of my splint stretcher can then be slid out from under the person being 60 treated, and the foot portion 26 can likewise be slid out from under the person being treated. In this way the splint stretcher is removed from the person being treated or 65 carried thereon, thereby avoiding the lifting of the person being treated from said splint

stretcher, and in this way eliminating the danger of further injury through the lifting of the person being treated from my stretcher to the operating table or bed. 42 is a sanitary opening between the head portion 25 and the foot portion 26 at the necessary position, and serves an essential purpose to avoid the lifting or moving of the person under treatment.

Many variations can be made in the particular form of structure used to carry out my ideas without departing from the spirit and intent of my invention.

I claim:

1. In a splint stretcher a separable frame 80 comprising an outer frame member which at the point of separation has two tongue members mounted in the head portion of said frame adapted to engage the outer frame member of the foot portion, a circular boring in each of said tongues adapted to register with a circular boring in said outer frame foot portions, a pin adapted to secure said members together through said circular borings, longitudinal frame members the head portions of which terminate at the point of separation in cylindrical tubes, a cylindrical boring in said cylindrical tubes and semi-circular cutouts in the 90 foot portions of said frame members adapted to register with said borings and pins adapted to secure the same together.

2. In a splint stretcher a separable frame 100 comprising an outer frame member which at the point of separation has two tongue members mounted in the head portion of said frame adapted to engage the outer frame member of the foot portion, a circular boring in each of said tongues adapted to register with a circular boring in said outer frame foot portions, a pin adapted to 105 secure said members together through said circular borings, longitudinal frame members the head portions of which terminate at the point of separation in cylindrical tubes, a cylindrical boring in said cylindrical tubes and semi-circular cutouts in the 110 foot portions of said frame members adapted to register with said borings and pins adapted to secure the same together, substantially rigid meshwork secured to said frame, a portion of said frame being formed into gutters, a sanitary opening between said separable members and handle grips of larger tubing mounted on said frame.

3. In a splint stretcher a separable frame 125 comprising an outer frame member which at the point of separation has two tongue members mounted in the head portion of said frame adapted to engage the outer frame member of the foot portion, a circular boring in each of said tongues adapted to register with a circular boring in said outer frame foot portions, a pin adapted to 130 secure said members together through said

circular borings, longitudinal frame members the head portions of which terminate at the point of separation in cylindrical tubes, a cylindrical boring in said cylindrical tubes and semi-circular cutouts in the foot portions of said frame members adapted to register with said borings and pins adapted

to secure the same together, a substantially rigid meshwork secured to each of the separable frame parts and having leg gutters 10 and means for securing a patient in a fixed position to said stretcher.

In testimony whereof I affix my signature.
SYDNEY B. AUSTIN.
